UNITED STATES PATENT OFFICE.

JOHN B. STRAND, JOHN H. HAUGEN, WILLIAM COESFIELD, AND GEORGE FISCHRUPP, OF CHICAGO, ILLINOIS.

SOFA-BED.

No. 887,982.

Specification of Letters Patent.

Patented May 19, 1908.

Application filed January 18, 1908. Serial No. 410,593.

To all whom it may concern:

Be it known that we, JOHN B. STRAND, JOHN H. HAUGEN, WILLIAM COESFIELD, and GEORGE FISCHRUPP, citizens of the United States of America, and residents of Chicago, in the county of Cook and State of Illinois, have invented certain new and useful Improvements in Sofa-Beds, of which the following is a specification:

This invention relates to that type of sofa beds which constitute the subject matter of Letters Patent No. 816,134 issued March 27, 1906, to John B. Strand and John H. Haugen for improvements in sofa beds. And the present improvement has for its various objects: to provide a simple and effective connection between the reversible sofa bed member and its stationary supporting frame, and by which said reversible section is held and guided in its turning movements, and such movements attained with the exertion of but little force; to provide a simple and efficient structural formation and combination of parts in a folding bed frame carried by said reversible section, and in which the hinged sections of said bed frame are automatically brought into an elevated and even plane, as said sections are opened to form the bed surface and with a corresponding automatic descent of said sections as they are closed together after use as a bed; and also to provide means for locking the reversible sofa-bed section in its bed position against accidental turning, all as will, hereinafter more fully appear.

In the accompanying drawings illustrative of the present invention: Figure 1 is a vertical sectional elevation on line $x-x$ Fig. 2, with the reversible sofa-bed section shown in dotted lines in its sofa forming position. Fig. 2, is a fragmentary front elevation. Fig. 3, is a vertical sectional elevation with the reversible sofa bed section shown in full lines in its bed forming position and in dotted lines in a partially reversed position. Figs. 4, 5, 6 and 7 are transverse sections of the reversible sofa-bed section and its contained folding bed frame, and illustrating the movements of said folding bed frame from its closed or folded condition to a fully opened or unfolded condition. Fig. 8 is a detail vertical longitudinal section on line $x'-x'$ Fig. 7. Fig. 9 is a detail horizontal section on line x^2-x^2 Fig. 8. Fig. 10 is a fragmentary plan view, with the folding bed frame

in its open or unfolded condition. Fig. 11 is a similar view, with said frame in a closed or folded condition. Fig. 12 is a detail longitudinal section on line x^3-x^3 Fig. 10. Fig. 13 is a detail transverse section on line x^4-x^4 Fig. 12.

Similar numerals of reference indicate like parts in the several views.

Referring to the drawings, 1 represents the upright back member, and 2 the upright end members secured rigidly together to constitute the main stationary supporting frame or section of the sofa-bed.

3 is the reversible sofa-bed section secured to the aforesaid main frame in the pivotal and adjustable manner hereinafter described, and capable of a semi-rotation so that in one position it will constitute the seat portion of the sofa-bed, and in the other position present the folding bed frame hereinafter described, and which bed frame is adapted to be unfolded to present ample bed surface.

4 are radius-links pivotally secured near their rear ends to the inner faces of the end members 2 and near the rear ends of the same. The rear ends of such links extend to the rear of their points of pivotal attachment and are connected to one end of the tension springs 5, the opposite ends of said springs being attached to the main sofa-bed frame. Such springs are adapted to impart a constant upward stress upon the forward ends of the radius-links, with a view to aid in the movement of the reversible bed section from a sofa to a bed position. The forward ends of such radius-links are formed with open-top recesses 6 adapted for pivotal engagement with lateral studs 7 in the end boards 11 of the reversible sofa bed member 3, about the midwidth of the same. Such lateral studs are adapted to rest upon the tracks hereinafter described, to aid in the support of the reversible member 3, aforesaid. Such open top recesses 6 permit of a ready disconnection of the radius-links from the studs 7, in the operation of dismembering the bed for shipment and other purposes, as well as an operative connection of the appliances in an assemblage of the sofa-bed parts.

8 are tracks or slideways carried on the inner faces of the end members 2 of the main frame; such tracks are preferably inclined from the horizontal and in a downward direction towards the rear of the main frame, as shown in Figs. 1 and 3, and as in the before

mentioned patent No. 816,134, to attain a low position of the reversible bed member when the article is arranged as a sofa, and an elevated position of the reversible member 5 when the article is arranged as a bed.

9 are track wheels engaging the tracks or sideways 8, and secured to the respective ends of the reversible member 3, at points removed from the lateral studs 7 before described, and as shown in Figs. 1 and 3.

The operation of the parts above described, are similar to that in the aforesaid Letters Patent No. 816,134, and is as follows: In changing from a sofa to a bed form of the 15 article, an upward pull is made on the lower and forward edge of the reversible member 3, to tilt the same upwards with the track wheels 9 as a fulcrum and the radius-links 4 acting as a restraining means to prevent any 20 independent movement of the ends of the reversible member. With the progress of such tilting movement the track wheels 9 move forward on the tracks 8, the forward ends of the radius links 4 moving upwards in 25 consonance with such forward movement of the track wheels. Such forward movement of the track wheels continue until a full half turn has been imparted to the reversible member, with the attainment of such half 30 turn the track wheels are at the forward ends of the tracks and the radius links have returned to their original position and in contact with the tracks, to constitute in connection with the track wheels the entire 35 supporting connection between the reversible member and its stationary supporting frame. In changing the article back again from a bed to a sofa form the reverse of the above described operations will take place.

40 In the present construction the reversible member 3 is of a shell form, and comprises a horizontal member 10, the exposed surface of which is upholstered to form a sofa seat; a pair of vertical end boards or members 11, 45 and a vertical longitudinal board or member 12, as shown in Figs. 4, 5, 6, 7, 8, 9, 10 and 11, and as so constructed provides a receiving chamber for the folding bed frame now to be described.

50 13 is a longitudinal rail adapted to be secured to the reversible member 3, in manner hereinafter described, and provided at its respective ends with pivot brackets 14 to which are pivotally attached the folding frame hereinafter described, by elongated pivot pins or 55 pintles 15.

In the present construction the pintles 15 are formed with headed outer ends adapted for insertion in angular recesses 16 in catch 60 plates 17 secured to the end boards 11 of the reversible member 3, as shown more particularly in Figs. 12 and 13; the construction is such that said outer ends of the pintles will be initially introduced into said angular recesses 16, after which the longitudinal rail 13

will be pushed into place on the horizontal board 10 of the reversible member 3, and secured in place by a thumb-screw 18 or like fastening, see Figs. 4, 5, 6 and 7, to afford a substantial connection of said rail in place, 70 and at the same time permit of a ready detachment thereof when desired.

19 are T shaped links pivoted intermediate of their lengths and by their laterally extending arms 20, to the brackets 14, by the 75 said pintles 15.

21 and 22 are counterpart skeleton frame sections pivotally connected to the opposite ends of the aforesaid links 19 by hinge connections which permit of an independent 80 quarter turn between the parts when they are moved into their folded or unfolded positions as hereinafter more fully set forth. The aforesaid frame members 21 and 22, and intermediate links 19 constitute a marginal 85 supporting frame to which is attached any suitable elastic webbing, (not shown), and generally employed in sofa beds as the support for the ordinary bed mattress; in the folded condition of said parts, illustrated in 90 Fig. 4, the mattress will be inclosed by said parts as usual.

23 are pull bars pivotally connected to the intermediate links 19 at points adjacent to the pivotal attachment of said links to the 95 lowermost frame section 22 aforesaid.

24 are lifting levers pivoted to said lowermost frame section 22, with their lower ends having bearing upon the inclined tracks 25 secured to the end boards 11, of the reversible 100 section 3; while at their upper ends said levers are pivotally connected to the pull bars 23, as illustrated in Figs. 4, 5, 6 and 7.

With the described construction of folding bed frame, and in the unfolding movement of 105 the same the following operations take place serially:—The operator pulling upwardly on the free end of the uppermost frame section 21, moves the same into the vertical position shown in Fig. 5, without affecting the position of the other parts of the bed frame. Further outward and downward pulling by the operator upon such free end of the uppermost members 21 gradually tilts the intermediate links 19 from their previous vertical 110 position into a horizontal position, and said links in turn and in a direct manner and through the instrumentality of the pull bars 23, levers 24 and tracks 25 lifts the lowermost frame member 22 into an elevated plane 120 level with that of the uppermost frame member 21 and links 19. The various positions of the parts in the unfolding movements above described are serially illustrated in Figs. 4, 5, 6 and 7. In a folding movement 125 of the bed frame the reverse of the above described operations take place.

26 are a pair of vertically arranged shafts journaled on the longitudinal board of the reversible member 3, and provided with crank 130

arms 27 and 28 at their respective upper and lower ends, as shown in Figs. 4, 5, 6, 7, 8 and 9. In one position of said shafts the uppermost crank arm 27 is adapted to engage over the uppermost frame section 21 before described, to hold the same in place in the folded condition of the bed frame, and as shown in Fig. 4. In the other position of said shafts, said uppermost frame section 22 is released and free to be opened, and at the same time the lower crank arms 28 are adapted to lock the reversible member 3 to the main frame to prevent independent action between said parts, and to such end said crank arms 28 are operatively connected to latch bolts 29 guided in the reversible member 3, and engaging in keeper orifices 30 in the main frame, as illustrated in Figs. 8 and 9.

31 are hinged legs carried on the outer ends of the uppermost bed frame section 21, and adapted to support the same in its unfolded position for use as a bed.

Having thus fully described my said invention what I claim as new and desire to 25 secure by Letters Patent, is—

1. In a sofa-bed, the combination of a main frame formed by a back and end members having tracks on their opposed faces, a reversible member provided with track 30 wheels engaging said tracks, and with studs in spaced relation to the track wheels and adapted to have bearing on said tracks, radius links pivoted to the end members of the main frame and having pivotal connection 35 with said studs, and means for imposing an upward stress upon the forward ends of said links; substantially as set forth.

2. In a sofa-bed, the combination of a main frame formed by a back and end members having tracks on their opposed faces, a reversible member provided with track 40 wheels engaging said tracks, and with studs in spaced relation to the track wheels and adapted to have bearing on said tracks, radius links pivoted to the end members of the main frame and having pivotal connection 45 with said studs by open top recesses in the links, and means for imposing an upward stress upon the forward ends of said links, substantially as set forth.

3. In a sofa-bed, the combination of a main frame formed by a back and end members having tracks on their opposed faces, a reversible member provided with track 55 wheels engaging said tracks, and with studs in spaced relation to the track wheels and adapted to have bearing on said tracks, radius links pivoted to the end members of the main frame and having pivotal connection 60 with said studs, and tension springs connected to said links and adapted to impose an upward stress upon the forward end thereof, substantially as set forth.

4. In a sofa-bed, the combination of a 65 main frame formed by a back and end mem-

bers having tracks on their opposed faces, a reversible member provided with track wheels engaging said tracks, and with studs in spaced relation to the track wheels and adapted to have bearing on said tracks, 70 radius links pivoted to the end members of the main frame and having pivotal connection with said studs, and tension springs connected to rearwardly projecting ends of said links, substantially as set forth. 75

5. In a reversible sofa-bed of the type herein described, the combination with the reversible sofa-bed member, of a folding bed frame comprising a longitudinal rail secured to said reversible member, pivot brackets on 80 said rail, intermediate links pivoted to said brackets, counterpart marginal frame members pivoted to the respective ends of said intermediate links, and means intermediate of said links and one of said frame members 85 for imparting an upward movement to said frame member in an unfolding operation of the parts, substantially as set forth.

6. In a reversible sofa-bed of the type herein described, the combination with the 90 reversible sofa-bed member, of a folding bed frame comprising a longitudinal rail secured to said reversible member, pivot brackets on said rail, intermediate links pivoted to said brackets, counterpart marginal frame members pivoted to the respective end of said 95 intermediate links, and means intermediate of said links and one of said frame members in an unfolding operation of the parts, the same comprising intermediate pull bars, 100 levers and stationary tracks engaged by said levers, substantially as set forth.

7. In a reversible sofa-bed of the type herein described, the combination with the reversible sofa-bed member, of a folding bed 105 frame comprising a longitudinal rail secured to said reversible member, pivot brackets on said rail, intermediate T shaped links pivoted to said brackets, counterpart marginal frame members pivoted to the respective ends of 110 said intermediate links, and means intermediate of said links and one of said frame members for imparting an upward movement to said frame member in an unfolding movement of the parts, substantially as set forth. 115

8. In a reversible sofa-bed of the type herein described, the combination with the reversible sofa-bed member, of a folding bed frame comprising a longitudinal rail secured to said reversible member, pivot brackets on 120 said rail, intermediate T shaped links pivoted to said brackets, counterpart marginal frame members pivoted to the respective ends of said intermediate links, and means intermediate of said links and one of said frame members 125 in an unfolding movement of the parts, the same comprising intermediate pull bars, levers and stationary tracks engaged by said levers, substantially as set forth.

9. In a reversible sofa-bed of the type 130

herein described, the combination with the reversible sofa-bed member, of a folding bed frame comprising a longitudinal rail secured to said reversible member, pivot brackets on said rail intermediate links pivoted to said brackets, counterpart marginal frame members pivoted to the respective ends of said intermediate links, means intermediate of said links and one of said frame members for imparting an upward movement to said frame member in an unfolding operation of the parts and means for removably securing the longitudinal rail to said reversible member, the same comprising plates secured to the reversible member and having angular receiving recesses, pintle pins carried by said rail and adapted for engagement in said recesses, and a thumb screw for securing the rail in place, substantially as set forth.

10 10. In a reversible sofa-bed of the type

herein described, the combination with the main frame and reversible sofa-bed member, of a folding bed member carried by said reversible member, a shaft journaled in said reversible member and having a crank at one end for holding engagement with the folding bed frame and a secondary crank at the other end, and a locking bolt adapted for locking engagement with the main frame and operatively connected to said secondary crank arm substantially as set forth.

Signed at Chicago, Illinois this 9th day of January, 1908.

JOHN B. STRAND.
